STRINGED MUSICAL INSTRUMENT

Verlan L. Downing, 15011 SE. 51st, Bellevue, Wash.

Filed Aug. 8, 1960, Ser. No. 61,667

Term of patent 7 years

(Cl. D56—1)

I claim:

The ornamental design for a stringed musical instrument, substantially as shown.
